UNITED STATES PATENT OFFICE.

FREDERICK S. DEITRICK, OF CAMBRIDGE, AND EMILE C. FRANZMANN, OF SOMERVILLE, MASSACHUSETTS; SAID FRANZMANN ASSIGNOR TO SAID DEITRICK.

SAFETY-RAZOR.

1,295,972.

Specification of Letters Patent. Patented Mar. 4, 1919.

Application filed May 31, 1917. Serial No. 171,967.

To all whom it may concern:

Be it known that we, FREDERICK S. DEITRICK and EMILE C. FRANZMANN, citizens of the United States of America, and residents of Cambridge and Somerville, respectively, both in the county of Middlesex and State of Massachusetts, have invented new and useful Improvements in Safety-Razors, of which the following is a specification.

This invention relates to cutting devices and more particularly to safety razors. The principal objects of the invention are to provide a device of this character which is adapted to use blades of different styles, having either single or double edges, which is adapted to clamp a blade in operative position quickly and firmly and to clamp a doubled-edged blade in such position that either edge may be utilized with safety, which preferably has no threaded connections, which is neat and attractive in appearance, and which is relatively inexpensive to manufacture. Other objects are to provide a honing or stropping attachment, which is preferably employed in conjunction with the razor and which is adapted to accommodate either single-edged or double-edged blades.

Still further objects of the invention will be apparent from the following description taken in connection with the accompanying drawings, in which,—

Figure 1 is a side elevation of one embodiment of the invention, showing a single-edged blade in operative position;

Fig. 2 is a top plan view of the device shown in Fig. 1, a portion being broken away;

Fig. 3 is a side elevation of a portion of the device viewed from the left of Fig. 1, parts being broken away;

Fig. 4 is a vertical transverse central section through the device showing parts in elevation;

Fig. 5 is a transverse section taken on line 5-5 of Fig. 3, showing the means for locking the parts in position;

Fig. 6 is a top plan view of the stropping attachment;

Fig. 7 is a transverse section taken on line 7-7 of Fig. 4, showing a single-edged blade in position in the stropping attachment; and

Fig. 8 is a transverse section taken on line 8-8 of Fig. 4, showing a double-edged blade in position in the stropping attachment.

The particular embodiment of our invention, chosen for the purpose of illustration, comprises a handle 1, upon the upper end of which is mounted a guard member 2 having two operating edges provided with rows of teeth 3 and 4, respectively, a blade positioning means 6, a blade holding means 7, a locking arm 8 mounted on the holding member 7, and cam members 9 mounted inside of the handle 1 in such manner as to coöperate with cam slots 11 in the locking arm 8 in a manner hereinafter to be described. While the handle 1 may be of any suitable contour and construction in the broader aspect of the invention, it is preferably hollow, as indicated, so that the locking arm 8 which coöperates with the handle to lock the parts in operative position may extend into the handle, thereby to make the device more compact.

A cardinal feature of the invention consists in the functional relationships between the guard member 4, the positioning means 6 and the holding member 7. The guard member 4 is preferably convex transversely, although it may, if desired, be made flat on its upper surface. The holding means 6 is disposed over the guard member adjacent one of the rows of teeth, namely, the row 3. The primary function of the holding means is to position a blade in operative relationship to the row of teeth 3. In the preferred embodiment of the invention the means is so arranged that either a single-edged blade, such as shown at 12 in the figures, or a double-edged blade lying along the surface of the guard member may be held in operative relationship to the teeth. To this end the outer side of the positioning means 6 is preferably disposed in close proximity to the surface of the guard member near the row of teeth 3, the space between the outer edge of the holding means and the guard member being preferably a little more than sufficient to permit a thin blade to be inserted therebetween. The shape of the positioning means back of the forward edge is of lesser importance, but in the preferred embodiment the said portion is made

substantially flat and is disposed obliquely with respect to the surface of the guard member, as shown in Figs. 1 and 4.

As shown in the drawings, the holding means 6 is in the form of a flat band or strap and is mounted at its opposite ends to the guard member 2 by means of ears 13. Projections 10 are preferably provided on the lower side of member 6 for the blade to bear against when employing a single-edged blade. In the illustrated embodiment of the invention the projections 10 are formed by indenting the member 6 at suitable points. Stops 5 may if desired be disposed at the ends of the guard member in front of the strap 6 to limit the forward movement of the single-edged blade when inserted under strap 6.

In order to hold a double-edged blade in position the holding member 7 is provided with a portion 14 disposed on the right-hand side (Figs. 1, 2 and 4) of the longitudinal central region of the guard member 2 so as to clamp the blade between this member and the guard member on the right-hand side, the blade being held against the guard member on the left-hand side by the outer edge of the strap 6. In order to adapt the holding member 7 to hold a single-edged blade in position it is provided with a portion 9 on the left-hand side of the longitudinal central region of the guard member, this portion extending into operative relationship with the single-edged blade 12 so as to hold the blade against the positioning means 6 when in the normal position shown in Figs. 1 and 4. The portion 16 is preferably provided with a flat surface 17 so disposed as to bear against the blade 12 throughout its entire width. The portion 16 also extends upwardly from the guard member 2 to permit the holding member 7 to be rotated about the longitudinal central region of the guard member as will be hereinafter described.

In order to actuate the holding member 7 and maintain it in operative position, the locking arm 8 is preferably so mounted in the center of the lower face of the member 7 as to extend into the upper portion of the hollow handle 1. A slot 18 is provided at one side of the upper portion of the handle 1, and the locking arm 8 is so curved that its lower end projects slightly out of the handle 1 when in operative position. Owing to the fact that the portion 16 of the holding member 7 extends upwardly from the guard member, the holding member 7 and the locking arm 8 may be swung outwardly into the broken line position shown in Fig. 1 so that the locking arm 8 extends outwardly through the slot 18 in the handle 1. The cam members 9, which are preferably formed by striking up portions of the handle 1, have sloping portions 19, horizontal portions 21 and depending portions 22.

When the locking arm 8 is swung inwardly from the position shown in dot and dash lines in Fig. 1 to the normal position the slots 11 on opposite sides of the locking arm 8 engage the inclined portions 19 of the cam members 9, thereby drawing the holding member 7 downwardly against the guard member 2. When using a double-edged blade this serves to flex the blade in the well-known manner and force it into substantial parallelism with the convex guard member. The horizontal portions 21 of the cam members 9 are provided to hold the locking arm in normal position, as shown for example in Figs. 1 and 4, and the depending portions 22 are provided to limit the inward movement of the locking arm, these portions being arranged to engage the inner side of the locking arm just below the slots 11.

When it is desired to use a double-edged blade the arm 8 is swung outwardly into the broken line position shown in Fig. 1 and is then withdrawn upwardly from the upper end of the hollow handle. The double-edged blade is then placed in position on the guard member with the central opening ordinarily provided therein in alignment with the hollow handle. The arm 8 is then inserted through the opening in the blade into the broken line position shown in Fig. 1. The arm is then swung inwardly by pressing inwardly on the lower end thereof into the operative position shown in Fig. 4. In order more positively to position the holding member 7 on the guard member and more securely to position the double-edged blade on the guard member, pins 23 are provided on the holding member on opposite sides of the arm 8 so as to project through openings 24 in the guard member in the well-known manner. The openings 24 are so shaped as to permit slight movement of the pins therein when the holding member 7 is rotated about the longitudinal central region of the guard member.

The stropping attachment, forming a part of the present invention, comprises a tubular holder 31 having an enlarged portion 32 adapted to fit snugly within the lower end of the handle 1, as shown in Fig. 4, and having a portion 33 of slightly larger diameter on its lower end, the portion 33 preferably being of such internal diameter as snugly to fit over the lower end of the handle 1. By virtue of this arrangement the stropping attachment may normally be carried in the position shown in Figs. 1 and 2, and when it is desired to use the attachment for stropping purposes it may be withdrawn from the handle, reversed and fitted over the handle so that the handle of the razor may also be employed as a handle for the stropping attachment. The upper portion of the tubular stropping attachment is preferably split along a central

longitudinal plane so as to provide slots 34 and 36 on opposite sides thereof. For the purpose of holding a blade of the type shown in Fig. 7, or of any type of single-edged blade, the rear portion of which is relatively thick, guides 37 are preferably provided on the inside of the tubular attachment on opposite sides of the slots 34 and 36, the preferred method of providing these guides being to strike up lugs from the walls of the tubular members as shown in the drawings. In order to hold a double-edged blade in the stropping attachment a spring member 38 is provided, the member 38 being disposed within the attachment on one side of the plane of the slots 34 and 36 and being mounted in any suitable manner as indicated for example at 39. Projections 41 are preferably provided on the member 38 to coöperate with the holes ordinarily provided near the ends of the double-edged blade, the projections 41 being spaced apart a distance equal to the distance between the holes in the blade.

When employing the stropping attachment to strop a single-edged blade of the type shown in Fig. 7 the thick rear portion of the blade is inserted through the opening 42 (Fig. 6) in the upper end of the attachment and forced downwardly until the blade is wholly within the slot 34. By suitably positioning the lugs 37 the blade may be held rigidly in this position, and if desired the lugs may be made of such length as to have some flexibility, so as yieldingly to engage the opposite sides of the thick portion of the blade. When it is desired to strop a double-edged blade of the character shown in Fig. 8 for example, the blade is inserted into the attachment from the top in the same way as a single edge blade, the blade being passed into the attachment until the lugs 41 are forced into the spaced openings in the blade by the elasticity of the spring member 38. Thus a double-edged blade is firmly held in position by means of the lugs 41, while the single-edged blade is held in position largely by virtue of the lugs 37, although it is obvious that the pressure of the projections 41 against the single-edged blade when in the position shown in Fig. 7 tends to assist in maintaining the blade in position. In introducing the blade of either type into the holding attachment the projections 41 may be moved out of the path of the blade by pressing the end 44 of the member 38 outwardly.

I claim:

1. A safety razor comprising a double-edged guard member, and means for holding a blade in position on the guard member, the holding means having two blade engaging surfaces adapted to be used inde-

pendently to hold a blade in operative position with respect to one edge of said guard. 65

2. A safety razor comprising a double-edged guard member, and means for holding a blade in position on the guard member, the holding means having a surface for engaging a single-edged blade to hold the 70 blade in operative position relatively to one edge of said guard and having another surface for engaging a double-edged blade to hold the blade in operative position relatively to both edges of said guard. 75

3. A safety razor comprising a guard member, and means for holding a blade on the guard, said holding means having an inner surface adapted to clamp a thin flexible blade against the guard and having an 80 outer surface adapted to engage a relatively thick blade, whereby either a thin flexible blade or a relatively thick blade may be employed.

4. A safety razor comprising a double-edged guard member, and means for holding a blade in position on the guard member, said holding means having a lower surface adapted to clamp a double-edged blade against the guard with the cutting 90 edges in operative position to the respective edges of the guard and having an upper surface adapted to engage a single-edged blade to hold the blade in operative relationship to one edge of the guard, whereby 95 either a double-edged or a single-edged blade may be employed.

5. A safety razor comprising a guard member, a cap member disposed above the guard member, a hollow handle for the guard member, a handle for the cap member extending into the guard handle, and coöperating locking means on the two handles so arranged that when the cap member is rotated about a longitudinal region of the 100 guard member to clamp a blade between the two members the locking means on the handles coöperate to lock the parts in operative position.

6. A safety razor comprising a guard member, a cap member disposed above the guard member and having a portion disposed on one side of the longitudinal central region of the guard member so that the cap member may be rotated about said region to move said portion to and from the guard member, handles extending in juxtaposition from said members respectively, and locking means on the handles so arranged that when said portion of the cap member is rotated into juxtaposition to the cap member to clamp a blade between the two members the locking means on the handles lock the members in operative position. 115

7. A safety razor comprising a guard 120 member, a cap member disposed above the

guard member and having a portion disposed on one side of the longitudinal central region of the guard member so that the cap member may be rotated about said region to move said portion to and from the guard member, a hollow handle on the guard member, a locking arm extending into said handle from the cap member, cams disposed on the handle and arm respectively so as to lock the parts in operative position when the cap member is rotated into juxtaposition to the guard member to clamp a blade between the two members.

8. A safety razor comprising a guard member having teeth along one side, means disposed above the guard member in close relationship to said teeth for engaging the upper side of a blade, a member mounted to rotate about the longitudinal central region of the guard member to engage the blade on the under side and hold it against the said means.

9. A safety razor comprising a guard member having teeth along one side, a positioning member disposed above the guard member along said teeth so that a blade may be positioned between the two members with its forward edge disposed over said teeth, a holding member rotatably mounted behind said positioning member so as to engage the blade and hold it in position against the positioning member, and locking members connecting with the guard and holding members respectively to lock the parts in operative position when the holding member is rotated into operative position.

10. A safety razor comprising a guard member having two guard edges, blade positioning means disposed over the guard member adjacent one of the guard edges to hold a blade in operative position with respect to said one of the guard edges, and a blade holding member arranged to be rotated about the longitudinal central region of the guard member, the guard member being so shaped that, when rotated into normal position, it will clamp either a double-edged blade between said two members in operative relationship to the two edges of the guard member or a single-edged blade between the holding member and positioning means in operative relationship to said one guard edge.

11. A safety razor comprising a guard member having two guard edges, blade positioning means disposed over the guard member adjacent one of the guard edges so that a straight blade may thereby be positioned in oblique relationship to the guard member and in operative relationship to said one of the guard edges, a blade holding member disposed over the guard member, the holding member having a portion on the side of the longitudinal central region of the

guard member opposite to said one of the guard edges so arranged that a double-edged blade may be held beneath said positioning means and said holding member with its edges in operative relationship to the two guard edges, and the holding member having a portion on the other side of said longitudinal central region extending upwardly from the guard member so as to engage the under side of a single-edged blade and hold it against said positioning means with its cutting edge in operative relationship to said one of the guard edges, whereby either a single-edged or a double-edged blade may be employed.

12. A safety razor comprising a guard member having two guard edges, blade positioning means disposed over the guard member adjacent one of the guard edges so that a straight blade may thereby be positioned in oblique relationship to the guard member and in operative relationship to said one of the guard edges, a blade holding member disposed over the guard member, the holding member having a portion on the side of the longitudinal central region of the guard member opposite to said one of the guard edges so arranged that a double-edged blade may be held beneath said positioning means and said holding member with its edges in operative relationship to the two guard edges, and the holding member having a portion on the other side of said longitudinal central region extending upwardly from the guard member so as to engage the under side of a single-edged blade and hold it against said positioning means with its cutting edge in operative relationship to said one of the guard edges, whereby either a single-edged or a double-edged blade may be employed, and means extending through the guard member for rotating the holding member about said longitudinal region to move the holding member into and out of operative position.

13. A safety razor comprising a guard member having two guard edges, blade positioning means disposed over the guard member adjacent one of the guard edges so that a straight blade may thereby be positioned in oblique relationship to the guard member and in operative relationship to said one of the guard edges, a blade holding member disposed over the guard member, the holding member having a portion on the side of the longitudinal central region of the guard member opposite to said one of the guard edges so arranged that a double-edged blade may be held beneath said positioning means and said holding member with its edges in operative relationship to the two guard edges, and the holding member having a portion on the other side of said longitudinal central region extending upwardly

from the guard member so as to engage the under side of a single-edged blade and hold it against said positioning means with its cutting edge in operative relationship to said one of the guard edges, whereby either a single-edged or a double-edged blade may be employed, a handle on the guard member, a locking arm extending from the holding member into juxtaposition to the handle, co-

operative locking means on the handle and 10 arm respectively arranged automatically to lock the holding member in operative position when the holding member is rotated into normal position.

Signed by us at Boston, Massachusetts, 15 this twenty-sixth day of May, 1917.
